UNITED STATES PATENT OFFICE.

SEBASTIAN G. BRINKMAN, OF PERTH AMBOY, NEW JERSEY.

CARBURETOR.

Application filed March 24, 1923. Serial No. 627,356.

This invention relates to improvements in carburetors and more particularly to an improvement upon the carburetor illustrated and described in my Letters Patent No. 5 1,243,250, dated October 16th, 1917.

An object of the invention is to provide a carburetor with an annular fuel discharge nozzle and a double conical-shaped governor, rotatably mounted upon a coarse screw-threaded spindle, said governor being capable of upward and downward movement axially past said nozzle, and directly operable in accordance with the speed of the engine to which the carburetor is attached.

15 A further object of the invention is to provide a carburetor with an annular fuel discharge nozzle, and a tapered metering cone threaded into the base of the carburetor body, the same being operable from a point 20 adjacent the steering mechanism, and adapted to meter the fuel drawn through the carburetor by the suction of the engine.

A still further object of the invention is to provide a carburetor having a widened or 25 flared annular fuel discharge nozzle and an annular fuel supply chamber, between which is formed a restricted annular fuel inlet. A considerable partial vacuum is maintained in this widened fuel discharge nozzle and 30 when the liquid fuel enters such discharge nozzle from the restricted inlet a portion of same is vaporized therein and a mixture of vapor and unvaporized fuel particles issues from such nozzle into the main air stream, 35 where such unvaporized particles are further broken up.

Other objects will appear as the description proceeds.

In the accompanying drawings which 40 form a part of my application,

Figure 1 is a sectional elevation taken through my improved carburetor;

Figure 2 is a sectional view taken on the line 2-2 of Figure 1, and

45 Figure 3 is an enlarged sectional detailed view of a portion of one side of the fuel chamber, metering cone, and adjacent parts.

Like characters of reference are used 50 throughout the following specification and the accompanying drawings to designate corresponding parts.

The body of my improved carburetor is expanded at 1, and is formed at its lower end with an outwardly flared skirt portion 2.

55 The upper end of the carburetor is slightly restricted at 3, where it is adapted to be at-

tached to the inlet manifold (not shown) of an internal combustion engine. The usual throttle or butterfly valve 4 is disposed within the portion 3 of the carburetor; to 60 regulate the flow of the incoming fuel mixture.

An inwardly extending flange 5 is formed at the lower end of the expanded portion 1, where such portion joins the skirt portion 2 65 of the body. Cooperating with this flange is an inwardly extending lip on a tapered metering cone 6, which is adjustable relative to the skirt portion 2 in a manner herein-after set forth, to control the flow of fuel, 70 and in all positions of adjustment of the element 6 the said lip is spaced from the flange 5 to form therebetween an enlarged or flared chamber which constitutes the fuel nozzle and functions in a manner hereinafter set 75 forth.

The outer wall of the hollow metering cone 6 is tapered at substantially 80 degrees to the horizontal, which is substantially the taper of the inner wall of the skirt portion 80 2. The space between these walls forms an annular fuel inlet passage, the cross-sectional area of which is adjusted by movement of the metering cone relative to the body portion. To permit movement of the cone 6, the latter is externally screw-threaded as at 7 adjacent its lower end where it engages the internal screw thread on the skirt portion 2 of the carburetor body. A laterally extending arm 8 is formed at the lower end of the cone 6 and has connected thereto a rod 9 which is adapted to extend to the dash of an automobile or other point convenient to the operator. There are approximately thirty threads to the inch on 85 the base of the element 6, so that the element can be adjusted through very small vertical distances with correspondingly small variations in the cross-sectional area of the fuel 90 passage.

An annular flange 10 is formed at the lower end of the metering cone 6 and is internally screw-threaded at 11 to receive a flanged, threaded nut 13 which serves to hold a gasket 12 between its flange and the cooperating flange of the cone 6. A seat 14 is formed adjacent the lower end of the cone 6 and an elbow-shaped air inlet pipe 15 is provided with a flange 16 at its upper end which abuts against the seat 14 when the device is assembled, being held in position by the nut 13, as indicated in Figures 1 and 3.

A choke valve 17 of ordinary type is provided in the air inlet to control the flow of incoming air in the usual way.

Extending through the wall of the air inlet pipe 15 and projecting vertically in the main intake passage is a spindle 19 which is provided with a threaded upper end, the threaded portion being provided with a thread of very steep pitch. Mounted on the 10 spindle for rotation thereon is a governor element 18. This governor element has a bushing 20 screwed into its lower end and secured in a recess at the upper end of the governor is a plug 21 having an internal 15 thread thereon to cooperate with the threaded portion of the spindle 19. The bushing 20 seats on a plug in the air inlet pipe, as shown in Figure 1, and such bushing may be adjusted in the governor element to regulate 20 the normal position of such element when the associated engine is not running. It will be noted on inspection of Figure 1 that in normal position that portion of the governor element which is of greatest cross-sectional area occupies a position adjacent the fuel outlet nozzle. When the throttle 4 is opened the suction of the engine lifts the governor element to enlarge the main intake 25 passageway until at maximum opening it occupies the position shown in dotted lines in Figure 1. As the element rises it rotates, owing to engagement of the plug 21 with the threaded part of spindle 19 and this same arrangement acts somewhat in the manner of a dash pot and prevents fluttering of the governor element. This governor element serves not only to control the area of the intake passage, but also acts as a baffle 30 against which any unvaporized particles of fuel issuing from the nozzle may strike, thus assisting in breaking up such portions of the fuel as are not vaporized in the flared nozzle outlet. A fuel supply pipe 22 is threaded into the skirt portion 2 of the carburetor body and communicates with the fuel supply 35 chamber 23.

From the foregoing description, it will be apparent that the mode of operation is as follows: Assuming that the carburetor is 40 attached to an internal combustion engine, the governor will normally rest in its lowermost position when the engine is idle. As soon as the engine is started, the fuel passes from the fuel supply chamber, through the 45 annular fuel inlet passage and is partially vaporized as it passes through the widened fuel discharge nozzle, due to the partial vacuum therein. By manually rotating the metering cone, more or less fuel will be fed 50 into the mixing chamber of the carburetor. When the speed of the engine increases, there is a corresponding upward movement of the governor, dependent entirely upon the speed 55 of the engine. As the governor raises, a large 60 passage is created through which the mix-

ture may pass. It will be seen on inspection of Fig. 1 that there will always be an unrestricted passage from the discharge nozzle to the inlet and into the intake manifold.

The metering cone provides an efficient 70 and extremely gradual and sensitive feeding control of the fuel to the carburetor.

The metering cone is connected so as to be operable from a point adjacent the steering mechanism. When my carburetor is once 75 attached to an engine, it will require no attention after being first adjusted.

Many minor changes in detail of construction may be resorted to without departure 80 from the spirit of the invention.

Having thus described my invention what I claim as new and desire to secure by Letters Patent of the United States is:

1. A carburetor comprising a main air 85 passage, a fuel inlet passage formed in the wall thereof and communicating with said air passage and a main fuel supply, said fuel inlet passage comprising an annular fuel chamber extending circumferentially around the wall of the shell, the outlet of said fuel 90 inlet passage being enlarged to form a nozzle of greater cross sectional area than the main portion of said fuel inlet passage, to provide a chamber in which the fuel is partially vaporized before mixing with the 95 air in the main air passage.

2. A carburetor comprising a main air 100 passage, a fuel inlet passage formed in the wall thereof at an approximate angle of 80 degrees to the horizontal and communicating with said air passage and a main fuel supply, said fuel inlet passage comprising an annular fuel chamber extending circumferentially around the wall of the shell, a governor movable within the shell, the outlet of said fuel passage being inwardly directed towards said governor and enlarged to form a nozzle of greater cross 105 sectional area than the main portion of said fuel inlet passage, to provide a chamber in which the fuel is partially vaporized before mixing with the air in the main air passage.

3. A carburetor comprising a main air 110 passage, a fuel inlet passage formed in the wall thereof and communicating with said air passage and a main fuel supply, said fuel inlet passage comprising an annular fuel chamber extending circumferentially around the wall of the shell, a double cone-shaped governor movable within said shell, the outlet of said fuel inlet passage being inwardly directed towards said governor opposite the apex thereof and enlarged to 115 form a nozzle of greater cross sectional area than the main portion of said fuel inlet passage, to provide a chamber in which the fuel is partially vaporized before mixing with the air in the main air passage.

4. A carburetor comprising a main air 120

- passage, a fuel inlet passage formed in the wall thereof and communicating with said air passage and a main fuel supply, said fuel inlet passage comprising an annular 5 fuel chamber extending circumferentially around the wall of the shell, the outlet of said fuel inlet passage being enlarged to form a nozzle of greater cross sectional area than the main portion of the said fuel 10 inlet passage, and a cone-shaped governor rotatably and vertically movable within the shell past said enlarged outlet of the fuel inlet passage directly responsive to the speed of the engine to which the carburetor 15 is attached.
5. A carburetor comprising a main air passage, a fuel inlet passage formed in the wall thereof at an approximate angle of 80 degrees to the horizontal and communicating with said air passage and a main fuel supply, said fuel inlet passage comprising an annular fuel chamber extending circumferentially around the wall of the shell, a governor movable within said shell, 20 the outlet of said fuel inlet passage being inwardly directed towards said governor and
- enlarged to form a nozzle of greater cross sectional area than the main portion of said fuel inlet passage, and means for effecting an adjustment between the walls of said fuel inlet passage. 30
6. A carburetor comprising a main air passage, a fuel inlet passage formed in the wall thereof and communicating with said air passage and a main fuel supply, said fuel inlet passage comprising an annular fuel chamber extending circumferentially around the wall of the shell, a screw positioned centrally of said main air passage, a cone-shaped governor rotatably and vertically movable on said screw, the outlet of said fuel passage being inwardly directed towards said governor and enlarged to form a nozzle of greater cross sectional area than the main portion of said fuel inlet passage, 40 to provide a chamber in which the fuel is partially vaporized before mixing with the air in the main air passage. 45

In witness whereof, I have signed my name to the foregoing specification.

SEBASTIAN G. BRINKMAN.
